LOAD DISCHARGING CAR

Argyle Campbell, Chicago, Ill., assignor to Enterprise Railway Equipment Company, Chicago, Ill., a corporation of Illinois

Application November 8, 1937, Serial No. 173,369

5 Claims. (Cl. 105—291)

My invention relates to improvements in load discharging cars of the type adapted to have doors in the floor for the discharge of the load by gravity.

5 An object of my invention is to provide an improved car of the type having hinged dumping doors adapted to be raised to closed position and supported in closed and opened position by means of winding mechanisms located above the level of 10 the doors.

Another object of my invention is to provide improved car construction adapted to be used in combination with improved door operating mechanisms for the purpose of strengthening the car 15 structure while economizing in dead weight.

Another further object of my improvements is to provide an improved operating mechanism of the self-locking linkage type which is composed of few parts and is located so as to offer no restriction to the discharge of lading when the doors 20 are in open position.

A still further object of my invention is to provide door operating mechanism of the self-locking linkage type which is placed directly above 25 the lower chord of a car side wall and is capable of supporting the doors in opened position without interference with the said lower chord.

A more specific object of my invention is to provide an improved mechanism and door structure which will permit of supporting the doors 30 at the respective side edges thereof and to provide means for adjusting the length of the door connections.

My invention also resides in the means provided 35 for housing the door linkage mechanisms and in the particular manner in which such housings are incorporated in the car structure to obtain great structural strength.

These and other improvements will be apparent 40 by reference to the following description and the appended claims.

The accompanying drawings illustrate one embodiment of my invention.

Fig. 1 is a vertical, longitudinal view in elevation of approximately one-half the length of a so-called general service car incorporating my 45 improvements;

Fig. 2 is a plan view of that part of the car 50 illustrated in Fig. 1, the upper half of the figure being a full plan view and the lower half being in section as taken substantially on the line 2—2 of Fig. 1;

Fig. 3 is a vertical transverse sectional view on 55 an enlarged scale taken through the lower part of the car body substantially on the line 3—3

of Fig. 1, said view showing the mechanism housing with the side wall removed;

Fig. 4 is a vertical elevational view of a portion of the side of the car illustrating the structure shown in Fig. 3, said view showing so much of the car as necessary to illustrate the construction at the middle of the car where the respective operating shafts on one side of the car terminate;

Fig. 5 is a vertical side view in elevation of the lower part of the car body on an enlarged 10 scale and illustrating that part of the car structure extending from one of the body bolsters to the end of the car; and

Fig. 6 is a fragmentary end view of the structure illustrated in Fig. 5 as viewed from right to 15 left, said view illustrating the shaft locking and rotating means.

My improvements are shown as applied to a car of the so-called general service type, in which the floor is of generally level floor construction 20 and mainly composed of dumping doors hinged adjacent the longitudinal center of the car and opening downwardly to discharge lading to the sides of the track.

In said drawings 10 indicates the center sill of 25 the car, having a flat cover plate 11. Extending laterally from said center sill, on each side thereof, are a series of transversely extending bracket beams 12, preferably in the form of pan-shaped diaphragms which include a vertical web 13 and 30 continuous marginal flanges 14. The diaphragms support transverse floor plates 15 and 16 respectively, which extend from side to side of the car. The plates 15 constitute the top cover plates of 35 the body bolsters and the plates 16 are the top cover plates of the crossbeams; the former are somewhat wider than the latter due to the fact that the bolsters make use of two diaphragms placed back-to-back, whereas the crossbeams utilize single diaphragms. The floor plates are 40 in all instances preferably wider than the supporting members in order to provide overhanging portions. The respective crossbeams and bolsters are also united along their lower margins by bottom cover plates 17 and 18 respectively. 45

The car is provided with vertical side walls, each formed of a plate 19 and top and bottom chords 20 and 21 respectively, the latter being preferably of Z-shape with the web 22 horizontally disposed and resting on the top of the diaphragms 12. The flanges 23 and 24 of the chord 22 respectively overlie the side-wall plate and the diaphragms 12, and are riveted thereto. Further connection between the members 12 and the side chord 22 is effected through the medium of 50 55

gusset plates 25 which are secured to the ends of the members 12 and are preferably welded to the lower chord as indicated at 26. At each cross-member there is provided a vertical side stake 27, preferably of Z-shaped formation, and disposed with its web 28 outstanding from the car wall and lying substantially in alignment with the center of the crossmembers. The side stake is coped out as indicated at 29 to conform to the shape of the lower chord, and the parts are united by welding as indicated at 30 and 31.

The ends of the car each include a vertical plate 32 reinforced at the top by a beam member 33 and at its lower margin on the outer side thereof by an end sill 34, the latter being preferably a Z-shaped member similar to the lower side chord. On the inner side of the car end wall, at the lower margin thereof, there is a flat floor plate 35 disposed on the same level as the bolster 20 and crossbeam floor plates.

Interposed between the various floor plates which extend transversely of the car are dumping doors 36 pivotally mounted adjacent the center sill of the car on hinge brackets 37 and extended 25 outwardly towards the side of the car in underlying relation with respect to the transversely extending floor plates and lower side chord.

The doors are adapted to be operated by means of operating shafts 38 and self-locking linkage 30 mechanisms 39 connecting the shafts and doors and adapted to raise the doors by rotation of the shaft and support the doors in both closed and open positions. Each shaft is adapted to operate a plurality of doors in unison and in this 35 particular embodiment of my invention there are twelve doors in the floor of the car adapted to be operated in multiples of three doors each.

The operating shafts 38 extend through the side stakes of the car and are carried in bearings 40 40 and 41, the former being secured to the stakes and the latter being disposed at the end of the car and serving as a carrying means for shaft locking means. The shafts are located outwardly of the load-carrying portion of the car and directly 45 above the lower chord of the car side wall.

The linkage mechanisms 39 are located at the ends of the doors and out of the path of the discharging load. Inasmuch as the mechanisms are of similar construction, the description herein will 50 be confined to only one of such mechanisms.

The mechanism 39 includes a hub member 42 non-rotatably mounted with respect to the shaft, it being understood that the shafts are preferably formed of non-circular section and 55 caused to rotate freely in their bearings by reason of having bushings 43 mounted on the shaft at each bearing. The hub is secured against lengthwise movement on the shaft by a pin or rivet 44. The hub is of polygonal shape and 60 includes a plurality of bearing faces 45, 46, 47 and 48 respectively, on which link members 49, 50 and 51 are adapted to bear. The links 49 and 51 which constitute the end links of the winding connection are of substantially equal 65 thickness and lie in a common plane of rotation.

The hub is formed with a pair of spaced integral jaws 52-52 between which one end of end link 49 is extended, and said link and jaw are pivotally united by riveted pin 53. The other 70 end link 51 constitutes the terminal link of the connection and is formed at one end with an upper hook-shaped portion 54 which bears on the seat 47 of the hub. The other end of the connection is extended downwardly through the 75 car side and through the aligned fixed floor

plates to a location below the floor level of the car for connection with the door in a manner to be hereinafter pointed out. The respective end links are sandwiched between a pair of spaced link members which constitute the intermediate link connection 50. The link means 50 include at each end integral ferrules 55 which form the pivots around which the end links flex, said ferrules operate to space the links and are formed with openings through which rivets 56 10 extend for uniting the parts.

The outer end of the hook-shaped terminal connection is formed concentrically as at 57 with respect to the pivotal axis of ferrule 55. Lying adjacent to the end of the said link, and 15 between the spaced links 50, is a projection 58 formed integrally with the hub, said projection being adapted to engage with the end of the terminal link in order to maintain the link members in definite relation to the hub in the event 20 that any of the doors might bind and fail to open when the shaft is rotated in an unwinding direction, such as sometimes occurs when the lading in the car is frozen. In the event of a door binding, the projection engages with the 25 terminal link and functions as a pusher to compel movement of the link in the indicated direction (Fig. 3) with consequent forcing of the door to open position. The links 50 are each formed with an indented body portion 59 which 30 straddles the hub when the doors are in closed position, and when the doors are in open position said indents straddle the lower chord of the car side, as indicated as 60 by the conventional dot and dash lines.

Openings 61 are provided in the car sides for the accommodation of the mechanisms and said openings lie immediately above the lower chord of the car side and immediately adjacent the side stakes at the intermediate part of the car side wall. At the end of the car the openings are located immediately adjacent the end wall of the car. In certain instances the flanges of the side stakes are coped out as indicated at 62 and 63 (Fig. 4) respectively to accommodate the mechanisms. Openings for the link mechanisms are also formed in the floor plates by means of cut-away portions 64 which have the effect of narrowing the fixed floor plates to a width corresponding substantially to the 50 width of the members 12 which underlie the bolster and crossbeam top plates.

Disposed above the link mechanisms and covering the openings in the side walls and floor plates, there are provided housings A. These 55 housings are disposed above the floor plates at the ends of the car and over each fixed floor plate at the crossbeams and bolsters and correspond substantially in width to the width of the said floor plates. The housings are preferably 60 formed of box-shaped section with an upper load-shedding surface 65 and a wall plate 66 extending vertically lengthwise of the car and lying beyond the path of movement of the terminal link 51. The plate 65 is welded to the 65 car side at 67, and the plate 66 is welded to the associated floor plate at 68. The said respective plates 65 and 66 preferably correspond in width to the width of the floor plates and in effect constitute extensions of said plates to 70 engage with the side walls at an appreciable distance above the floor. The end walls of the housings consist of vertical plates 69 flanged at 75 to overlie the car side walls and riveted thereto at 71. The plates 69 are connected with the 75

remaining parts of the housing by welding as at 72, and also to the floor plates by a welded connection 73.

In the case of the housings associated with 5 the bolsters and crossbeams, an additional wall 74 (Fig. 3) is provided which extends parallel to the end walls 69 and serves to divide the housing into two sections. This additional wall is disposed in alignment with the side stake web 10 and the plate is riveted by its flange 70 to the flange of the side stake and is also welded to the floor plate as at 75, thereby obtaining a rigid construction to compensate for the weakness due to openings in the side walls and floor plates.

15 In order to connect with the depending portion of the terminal links 51, the doors 36 are formed of special construction. Each door is formed of a body portion consisting of a plate 76 flanged around the marginal edges 77. The 20 underside of the door is reinforced with beams 78 extending at right angles to the pivotal axis of the door from the hinged end towards the swinging edge. Adjacent the swinging edge of the door and parallel thereto, there is provided 25 a door beam 79 preferably of Z-shaped formation with its web 80 disposed at right angles to the main plane of the door and having one of its flanges 81 secured to the plate. The other flange 82 is spaced an appreciable distance from 30 the door plate. The beam 79 terminates adjacent the sides of the door and brackets 83 are secured to the ends of the beam and project beyond the side edges of the door to lie in the plane of the associated linkage of the operating mechanism. Each bracket 83 is preferably 35 in the form of a casting having a vertical web 84 riveted to the vertical web 80 of the beam and having upper and lower flanges 85 and 86 respectively secured to the flanges 81 and 82 40 of the beam. The bracket 83 includes a vertical wall 87 lying adjacent and parallel to the side edge of the door. The wall 87 is extended downwardly below the beam 79 and is formed with a projecting horizontal ledge 88 at a lower level than the bottom flange 82 of the said beam 79.

The ledge 88 is braced to the main body of the bracket by braces 89 and 90, and extending through the said ledge is a threaded eyebolt 50 91 adapted to receive a nut 92 on its underside to bear against the ledge. Above the ledge, the eyebolt 91 is formed with a pair of jaws 93 which straddle the link member 51 and pivotally unite therewith through the medium of a pintle 94 which also extends through a slot 55 95 in the wall 87. One of the jaws 93 of the eyebolt 91 lies substantially in the plane of the flange of the door and in order to accommodate the said eyebolt portion the door flange is cut away at 96.

With the door in closed position and the linkage mechanism in operative locking position, as shown in Fig. 3, the pivotal axis of pintle 94 lies to one side of the bottom chord and in a different vertical plane from the axis of the shaft, and in order to render the mechanism self-locking the respective parts of the mechanism and door are so disposed that a straight line 97 (Fig. 3) joining the pivotal axes of the terminal link 51 will lie slightly to one side of the axis of the shaft, so that the weight of the door will lock the shaft against rotation in an unwinding direction. The strain on the upper pivotal connection of the hook-shaped link is partially relieved through the medium of bear-

ing surface 47 which lies substantially at right angles to the line 97.

Rotation and locking of the shaft is effected from the end of the car and for this purpose the shaft is extended lengthwise for a limited 5 distance beyond the end wall of the car and provided at said extended end with an operating ratchet wheel 98 with which is associated an oscillatably mounted lever-receiving socket 99. The socket includes a pair of spaced vertical walls 100—100 between which is mounted a pivotally movable pawl 101, whereby intermittent ratchet movement is permitted between the shaft and lever socket for the purpose of effecting rotation of the shaft in either direction.

15 The shaft is secured against unwinding movement during the raising operation of the doors by reason of the interengagement between a locking pawl 102 and a locking ratchet wheel 103, the former being carried on bracket 41 and the latter being fixedly mounted on the shaft. The pawl 102 is in turn secured against accidental disengagement from operative locking position by means of a pivotally mounted cam 104 which is also mounted on the bracket 41. For the purpose of providing a suitable mounting base for the locking pawl and cam, the bracket 41 is provided with a plate portion 105 which extends at right angles to the car wall, and the pawl and cam are provided with an overlying tie plate 106. The disposition of the mechanisms at the ends of the doors permits the concentration of the door links and shaft locking means in a small space near the corner of the car and permits the application of the side ladder 107 20 adjacent the car end and yet out of the path of the link mechanism.

25 With my improved construction I am enabled to employ a self-locking linkage mechanism notwithstanding the fact that the lower chord of the car side is an obstruction to the passage of the mechanism, and furthermore I am enabled to place the mechanisms at the ends of the doors where they are out of the path of the discharging load when the doors are in opened 30 position. The mechanisms are accessible for inspection and maintenance, and due to the fact that the linkage mechanisms wind substantially in a single plane of rotation, they are unusually compact and capable of being contained 35 in comparatively small housings.

40 I claim:

1. A railway load discharging car of the character described including a center sill, side walls including a substantially vertical plate section and a lower marginal chord of appreciable width, fixed floor sections extending transversely of the car between the side walls; dumping doors disposed intermediate the fixed floor sections, said doors being hingedly mounted adjacent the center sill; means for operating the doors including an operating shaft journaled outwardly of the car side plate section directly above the lower chord, and self-locking linkage mechanisms adapted to wind on the shaft and support the doors in open and closed positions, including terminal links adapted to extend above the lower chord and pivotally connect with the door inwardly of the car wall at one side of the chord, said terminal links of the respective doors extending at the sides of the door through openings formed in the fixed floor sections; and housings disposed above the openings and corresponding substantially in width to the width of the fixed floor sections, said links of the mechanisms 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955

- being of the rigid type and pivotally united together and so related to each other and to the car structure as to move without interference with any part of the car structure in any position of the doors.
2. A load discharging railway car of the character described, said car having a load-containing body portion including vertical side plate wall sections reinforced at the lower margin with an outstanding horizontal chord of appreciable width, said wall plates being also reinforced with vertical stakes having a vertical web lying substantially at right angles to the vertical side wall plate, said car having a longitudinal center sill and transverse beam members, each formed with a comparatively narrow beam section and a relatively wider surmounting flat floor plate, each said floor plate adjacent the side wall of the car being formed with a cut-away portion on each side of the vertical beam to present a recess on each side of the floor plate; dumping doors located intermediate the floor plates and hinged at one end adjacent the center sill and adapted to have their swinging edge supported adjacent the car side wall; supporting means for the swinging edges of the doors, including shafts pivotally mounted in the side stakes, said shafts being disposed above the lower chord; and mechanisms connecting the shafts and doors and located at the sides of the doors, and each including a terminal link adapted to extend through the side wall plate and to one side of the chord and through one of the recesses provided by the cut-away portions of the fixed floor plates, to connect with the doors below the load contacting surface thereof in such a manner that a line passing through the axes of the terminal links will pass substantially through the axis of the shaft when the doors are in closed position.
3. In a car of the character described, having a load-containing body portion defined in part by side walls each formed of a plate section reinforced at its lower margin on the outer side thereof by a chord member of appreciable width, and a floor including a longitudinally extending center sill top member and comparatively narrow floor sections extending transversely of the car, and dumping doors intermediate the floor sections, said doors being hinged adjacent the center sill and having their swinging edges adjacent the side wall of the car, said floor sections adjacent the side wall being formed with narrow end portions to present openings in the floor adjacent each side edge of each door; means for supporting the swinging edges of the doors, including operating shafts mounted above the lower chords and self-locking linkage mechanisms adapted to connect the shafts and doors, said linkage mechanisms being adapted to extend through the car side walls and through the openings in the floor above the lower chord to connect with the doors below the level of the floor and below the level of the floor of the door; and housings extending above the mechanisms and floor openings, and adapted to be rigidly

united with the floor sections and side walls and to function as brackets to brace the walls relatively to the floor.

4. A railway car of the character described, having a load-containing body portion including an upstanding wall and a floor including a longitudinally extending center sill top member and comparatively narrow floor plate sections extending transversely of the car, and dumping doors intermediate the floor plates, said doors being hinged adjacent the center sill and adapted to be supported adjacent their swinging edges, said wall plate being reinforced on its outer side by vertical stakes disposed in alignment with the floor plates, each side stake having an outstanding web centrally disposed with respect to the floor plate; means for supporting the doors including operating shafts mounted in the side stakes and self-locking linkage mechanisms connecting the shafts and doors, said linkage mechanism being extended in the plane of the load-containing body portion and through the car side wall and floor for connection with the door at a level below the level of the floor of the car, said wall and floor having openings therein for the passage of the mechanisms; and housings adapted to extend over the openings in the wall and floor and house the mechanisms, said housings including vertical wall plates extending transversely of the car and substantially in alignment with the respective edges of the floor plate and another wall plate disposed substantially in alignment with the web of the associated stake and adapted to divide the housing in two sections, said transverse plates being secured to the wall and floor plates respectively, and constituting brackets adapted to brace the floor and wall together.

5. In a railway car having a wall and a lower chord extending laterally from said wall; a dumping door adapted to extend beneath the lower chord when said door is in closed position; a door-operating and supporting shaft mounted above the chord; and a connection extending between the shaft and the door, said connection including a series of rigid links pivotally united and a hook-shaped terminal link pivotally attached to the door at its lower portion at a location to one side of the chord, said terminal link having its upper pivotal axis of attachment with the other links so disposed that when the door is in closed position a straight line extending through the lower and upper pivotal axes of the link will intersect the plane of the car side wall and pass above the lower chord to one side of the axis of rotation of the shaft whereby the weight of the door will lock the shaft against rotation in an unwinding direction, said winding mechanism being also adapted to support the doors in opened position and said links of the mechanism being so related to each other and to the car structure as to enable the mechanism to move clear of the car structure in any position of the mechanism.

ARGYLE CAMPBELL.
